BRUCE L. CUSHING, OF BUFFALO, NEW YORK.

HYGROSTAT.

1,282,196.

Specification of Letters Patent.

Patented Oct. 22, 1918.

Application filed September 4, 1917. Serial No. 189,695.

To all whom it may concern:

Be it known that I, BRUCE L. CUSHING, a citizen of the United States of America, and a resident of the city of Buffalo, county of Erie, and State of New York, have invented certain new and useful Improvements in Hygrostats, of which the following is a full, clear, and exact description.

My invention relates generally to humidifying apparatus and more particularly to an automatic means for controlling the percentage of moisture content in a room or enclosure.

The principal object of my invention has been to provide a hygrostat which will automatically control air valves or motors, whereby the moisture content of the air may be maintained at a predetermined point.

Another object of my invention has been to provide a hygrostat which will compensate for changes in temperature.

A further object has been to provide a device which will be very simple in its construction, as well as certain and reliable in its operation. Moreover, my device is simple and cheap to manufacture, and the parts are so arranged as to not easily get out of order.

The above objects and advantages have been accomplished by the combination and arrangement of parts shown in the accompanying drawings, of which:—

Figure 1 is an exterior view of my device on a reduced scale.

Fig. 2 is a transverse, vertical, sectional elevation, taken on line 2—2 of Fig. 1.

Fig. 3 is a transverse, sectional view, taken on line 3—3 of Fig. 2.

Fig. 4 is a transverse, sectional view taken on line 4—4 of Fig. 2.

Fig. 5 is a longitudinal, fragmentary, sectional view taken on line 5—5 of Fig. 4.

Fig. 6 is a bottom view of the compensating plate.

Fig. 7 is a transverse, sectional view, taken on line 7—7 of Fig. 2.

My device comprises a supporting member 8, which is provided with a flange 9 at each side thereof. These flanges are provided with suitable apertures, whereby the device may be secured to any suitable support.

Extending into the top of the base are two ports 10 and 11. They are each provided at their outer ends with screwthreads. To the outer end of the supply port 10 is

secured an inlet pipe 12, through which air under pressure is conducted to the device. An outlet air pipe 13 is screwed into the outer end of the outlet port 11 and connects 60 this port with the damper or valve which controls the spray inlets or other humidifying means employed. This damper or valve and the humidifying means do not form a part of my invention and are, therefore, 65 for clearness of illustration, not shown in the drawings. The humidifying damper or valve is of the normal pressure type—the type which operates when the pressure is released. A duct 14 connects the supply 70 port 10 with the outlet port 11; and engaging with the end of this port is the outer end of a regulating screw 15, carried by the supporting member 8. By means of this screw the amount of air passing into 75 the port 11 and through the outlet pipe 13 to the humidifying damper or valve is controlled. 16 is a relief valve which projects from the under face of the supporting member. This valve is provided with a central 80 aperture 17, which is open at its outer end to the atmosphere and connected at its inner end with the duct 14 by means of a valve duct 18. 19 is a valve lever, the outer end of which is arranged to close the central 85 aperture 17 and the relief valve 16. The inner end of this lever is carried by a spring 20 which keeps the outer end of the lever normally in contact with the outer end of the relief valve.

21 is a compensating plate which is arranged some distance below the supporting member 8. This plate is connected with the supporting member by means of two brass compensating rods 22 and two steel compensating rods 23. The steel compensating rods 23 are arranged near the center of the device and the brass compensating rods 22 are arranged near the free end of the valve lever 19. These rods are rigidly secured at 90 their upper ends to the supporting member 8, and are pivotally secured at their lower ends to the compensating plate 21. A pin 24 is carried by each of the rods near their lower ends between each pin and the compensating plate is arranged a helical spring 105 25, which serves to take up all the lost motion in the pivotal connection between the rods and compensating plate. At the side of the compensating plate, which is opposite to the brass compensating rods 22, is pivotally mounted a bell-crank lever 26 having an

outwardly extending arm 27 and an upwardly extending arm 28.

29 is the hygroscopic member of my device. This member comprises an upper disk 30 having a screw threaded stud 31, and a lower disk 32 having a screwthreaded stud 33. Each of the disks is provided with a plurality of perforations, and the hygroscopic strands are passed through the perforations and stretched between the disks. The perforations of the disks are preferably of a circular arrangement and the strands are arranged in a zig-zag manner. The stud 31, at the upper disk, is securely fastened to the inner end of the valve lever 19; and the stud 33 of the lower disk, is secured to the arm 27 of the bell-crank lever 26. As shown in Figs. 2 and 7, the disk 32 is provided with two outwardly extending ears 34, whereby a slot 35 is formed. In this slot is disposed the upwardly extending arm 28 of the bell-crank lever, whereby, when the stud 33 is adjusted, the disk 32 will be prevented from rotating. The studs 31 and 33 are each provided with adjusting nuts, whereby the tension of the hygroscopic member may be altered. Arranged centrally of the compensating plate 21 is a regulating device which comprises a central shaft 36 to the upper end of which is attached an eccentric 37. A helical spring 38 is arranged about the shaft and disposed between the eccentric and the upper surface of the compensating plate. Beneath the compensating plate is arranged a stop collar 39, which is secured to the shaft 36 and provided with a stop arm 40. Arranged on the under side of the compensating plate are two stop pins 41 and 42, with which the stop arm 40 is engageable. The eccentric 37 is arranged to have its surface engage with the upwardly extending arm 28 of the bell crank lever 26; and the lower end of the shaft 36 is provided with a flattened surface 43, whereby the shaft may be conveniently rotated.

The supporting member 8 is provided with a downwardly extending screwthreaded portion 44, attached to which is an outer casing 45. This casing protects all of the working parts and is closed at its lower end by means of a cap 46. In this cap is provided a plurality of apertures 47 and a central aperture 48 which registers with the shaft 36. The lower end of the shaft 36 is just above the lower surface of this cap, whereby a key (not shown) is necessary to effect an adjustment so that the device cannot be tampered with by any unauthorized person. In the central part of the supporting member 8 is a vertical air passage 49, communicating with which is a horizontal air passage or aspirator duct 50, in the outer end of which is secured an aspirator cone 51. 52 is an aspirator nozzle which is secured to the base at the inner end of the

aspirator duct 50, and arranged to project a stream of air through the aspirator cone. The central aperture of the nozzle is connected with the air supply port 10 by means of an air passage 53.

When the device is in use, air from the supply pipe 12 will be forced through the aspirator, thus inducing a current of air to pass through the apertures 47 in the cap 46, over the hygroscopic member 29 and 70 through the aspirator ducts 49 and 50, and cone 51. By this means, a sample of the air is taken from the room or inclosure which is having its humidity controlled by the device. When the air contained within 80 the room has the proper humidity, the outer end of the valve lever 19 will close the relief valve 16, whereby the pressure of the air upon the humidity controlling damper or valve will keep such damper or valve 85 closed. If, however, the humidity of the sample of air drawn through the device is below the predetermined point, as is well known, the strands of the hygroscopic member 29 will shrink, thus shortening the 90 member, and, thereby, raising the valve lever 19, against the tension of the spring 20, and opening the relief valve 16, more or less depending upon the dryness of the 95 sample of air. When the relief valve is 100 opened, the air pressure in the air controlled system is thereby reduced, which allows the humidifying dampers or valves to be operated and thereby supply additional moisture to the room or inclosure. The predetermined point at which the relief valve will be operated can be controlled by means of the eccentric 37, which, when rotated, will move the arm 27 toward or away from the valve lever 19.

When temperature changes occur within the room or inclosure the compensating rods 22 and 23 will operate to keep the pivotal point of the bell-crank lever 26 at substantially the same distance from the pivotal 110 end of the valve lever 19. The co-efficient of expansion of the brass rods 22 being greater than the co-efficient of expansion of the steel rods 23, this desired result is 115 accomplished.

While I have shown and described my device in connection with humidity controlling devices which are normally under pressure, it is obvious that I may use my device in connection with humidity controlling devices which are normally under no pressure. In adapting the device to the latter type of humidifying apparatus, it is only necessary that the spring pivotal point of the valve lever be placed at the opposite side of the 125 connection of the stud 31 thereto. Other modifications of the details herein shown and described may be made without departing from the spirit of my invention or the scope of the appended claims; and I do not, 130

therefore, wish to be limited to the exact embodiment herein shown and described.

Having thus described my invention, what I claim is:—

- 5 1. A hygrometer comprising a hygroscopic member formed of a series of strands arranged transversely of said member in a circular manner and longitudinally of said member in a zig-zag manner, said strands being made of a substance expansible and contractible under the influence of moisture, and means for mounting said strands.
- 10 2. A hygrometer comprising an upper peripherally perforated disk, a lower peripherally perforated disk, means for adjustably mounting the disks in the hygrometer, and a series of hygroscopic strands, threaded back and forth through the disk perforations, for connecting the disks.
- 15 3. A hygrometer comprising a supporting member, a compensating plate arranged opposite the supporting member, a plurality of compensating rods having different coefficients of expansion, each rigidly secured at one end to the supporting member and pivotally secured at the other end to the compensating plate, and a hygroscopic member arranged between the supporting member and the compensating plate, whereby the tension on the hygroscopic member is kept substantially uniform under varying temperatures.
- 20 4. A hygrometer comprising a supporting member, a compensating plate arranged opposite said supporting member, a plurality of compensating rods having different coefficients of expansion, each rigidly secured at one end to the supporting member and pivotally secured at the other end to the compensating plate, and a hygroscopic member arranged between the supporting member and the compensating plate, comprising a series of strands arranged transversely of said member in a circular manner and longitudinally of said member in a zig-zag manner.
- 25 5. A hygrometer comprising a supporting member, a compensating plate arranged opposite the supporting member, a plurality of compensating rods having different coefficients of expansion, each rigidly secured at one end to the supporting member and pivotally secured at the other end to the compensating plate, and a hygroscopic member arranged between the supporting member and the compensating plate, means for taking up lost motion between the rods and the compensating plate, and a hygroscopic member arranged between the supporting member and the compensating plate, whereby the tension on the hygroscopic member is kept

substantially uniform under varying temperatures.

6. A hygrometer comprising an upper peripherally perforated disk, a lower peripherally perforated disk, means for adjustably mounting the disks in the hygrometer, a series of hygroscopic strands, threaded back and forth through the disk perforations, for connecting the disk, and means for adjusting the tension of the hygroscopic strands.

7. A hygrometer comprising a supporting member, a compensating plate, means connecting the supporting member and the compensating plate, a hygroscopic member arranged between the supporting member and the compensating plate, and means for adjusting the tension on the hygroscopic member, comprising a bell-crank lever pivotally carried by the compensating plate and having one end of the hygroscopic member secured to one arm thereof, an eccentric engaging with the other arm of the bell-crank lever, and means for rotating the eccentric.

8. A hygrometer comprising a supporting member provided with unobstructed inlet and outlet ports for compressed air and a duct connecting the inlet and outlet ports, a relief valve carried by the supporting member and connected with the duct, a hygroscopic member, and means controlled by the hygroscopic member for operating the relief valve.

9. A hygrometer comprising a supporting member provided with inlet and outlet ports for compressed air and a duct connecting the inlet and outlet ports, a relief valve carried by the supporting member and connected with the duct, a hygroscopic member, a relief valve lever resiliently mounted on the supporting member for governing the office of the relief valve, and means for connecting one end of the hygroscopic member with the relief valve lever.

10. A hygrometer comprising a supporting member, a compensating plate, means connecting the supporting member and the compensating plate, a hygroscopic member arranged between the supporting member and the compensating plate, an aspirator formed within the supporting member, an outer casing secured to the supporting member and arranged about the hygroscopic member, and a perforated cap secured to the lower end of the casing, whereby a current of air is drawn by the aspirator through the casing and over the hygroscopic member.

In testimony whereof, I have hereunto signed my name.

BRUCE L. CUSHING
